OHIO

RADIO RECEIVING APPARATUS

Application filed July 15, 1927. Serial No. 205,938.

This invention relates to certain new and useful improvements in radio receiving apparatus.

Certain types of radio receiving sets embody a plurality of variable condensers which are generally arranged in a row and which are operated in unison by means of a knob or other device, and it is to that particular type of apparatus that this invention pertains.

The main object of the invention is the provision of a structure of marked rigidity and strength for supporting and connecting a plurality of variable condensers, and by means of which the desired central spacing of the condensers, i. e. the distance between the axes of their respective rotors, is rigidly and positively maintained.

Another object is to provide a means whereby the operation of the condensers may be at all times positive and smooth.

Other objects and advantages relate to the details of the structure and to the form and relation of the parts thereof, all as will more fully appear from the following description taken in connection with the accompanying drawings, in which:

Figure 1 is an elevation of a radio receiving cabinet.

Figure 2 is a section on line 2—2 of Figure 1.

Figure 3 is a top view of the condenser assembly and driving mechanism, partially broken away.

Figure 4 is an elevation of one of the driving wheels.

Figure 5 is a section on line 5—5 of Figure 3.

Figure 6 is a perspective view of the driving wire assembly.

Figure 7 is a section on line 7—7 of Figure 5.

Figure 8 is a section on line 8—8, Figure 2.

Figure 9 is a front elevation of the indicating dial.

In the drawings like numbers refer to like parts.

The invention here contemplates embodying a plurality of variable condensers, and in Figures 3 and 5 there are illustrated four

such condensers, but it will be understood that this disclosure is merely illustrative, and that any number of condensers may be mounted and connected together in the manner to be described.

As shown, four variable condensers —1— are mounted in line upon a strip —2— which may or may not be of an insulating material depending upon the type of radio receiving set. These condensers are affixed to the strip —2— in spaced relation by screws —3— or other convenient means, with their rotor shafts —4— and sleeves —11— extending through strip —2— and carrying on the ends of said rotor shafts —4— driving wheels —5—. The condensers —1— are also secured to sub-base —6— by screws —7— or other convenient means.

The variable condensers here shown comprise a U-shape frame —8— of sheet metal or the like, the legs —9— and —10— of this frame being formed with bearings at their lower ends for the reception of the rotor shaft —4—. The forward bearing, as shown, may be formed of a headed sleeve —11— which extends thru an opening in the arm —10— and has a nut —12— mounted thereon for securing the sleeve in the arm, and the rotor shaft is journaled in the sleeve —11—.

The condensers in the usual manner consist of a plurality of rotor plates —13— rigidly secured to the rotor —14— and a plurality of stator plates —15— rigidly mounted on cross-bars —16— and —16a— secured to the legs —9— and —10— the stator and rotor plates being alternately arranged.

The rear legs —9— of condensers —1— carry on their rear faces headed screws —44— fixed in position by nuts —45—. Spring wires —46— encircle screws —44— with their upper ends —47— extending through holes —48— in legs —9— and their lower ends —49— thrusting against V-slots —50— in rotor shafts —4—.

A dial wheel —17— carrying a hub —20— is rotatably mounted on shaft —18— having a shoulder 18a and which is secured to sub-base —6— by screws —19— or other convenient means. Dial wheel —17— is retained in position on shaft —18— by means of a col-

lar —21— and screw —22— threaded into the end of shaft —18—. An indicating dial —23— is fitted over hub —20— and retained in position by spring washer —24— which is 5 made in the form of a split ring fitting into a circumferential groove (not shown) in the end of hub —20—. This mounting of indicating dial —23— permits adjusting indicating dial —23— in relation to hub —20— if 10 such is desired.

A main driving wheel —25— is fastened to the front face of one of the driving wheels —5— and concentric therewith by means of screws —26— or other convenient means. 15 The specific construction of main driving wheel —25— and the take-up mechanism for driving cord —27— is not here described as it is disclosed in our co-pending application Serial No. 156,133.

20 An actuating knob —28— carrying a shaft —29— journaled in a bearing —30— is positioned in the front panel —31— of the cabinet —32—. The rear end of the shaft —29— carries a drum —33— held in position by set-screw —34— and having a circumferential groove for the reception of driving cord —27—.

Driving wheels —5— are provided with parallel circumferential slots —35— joined 30 by slot —36— positioned diagonally across the faces of driving wheels —5—, the advantage of this construction being that the wire does not at any time have two strands in one slot which would cause binding and uneven tension.

35 Dial wheel —17— is provided with a counter-sunk depression —37— in its rear face in which are positioned take-up screws —38— and lock screws —39—, and carries on its outer surface parallel circumferential slots —40— from each of which a hole (not shown) leads in depression —37—. Set screws —41— are provided to impinge upon the shanks of take-up screws —38— which are provided 45 with holes (shown in dotted lines in Fig. 8) for the reception of the ends of drive wire —42—.

A slot —43— in the front panel —31— permits the numbers on indicating dial —23— 50 to be seen as the same is rotated.

In assembly one end of the drive wire —42— is passed through one of the holes connecting slots —40— with depression —37— and fastened in place by means of the 55 take-up screw —38— and one locking screw —39—, the holes pointing downward. The drive wire —42— is then passed upwardly in slot —40— over the top of main drive wheel —17— and carried into a slot —35— on the 60 top of one of the drive wheels —5— which is at the end of the row of condensers —1—, the cross-slot —36— of the drive wheel —5— facing towards main drive wheel —17—. The drive wire —42— is passed around the 65 drive wheel —5— until it reaches cross-slot

—36— into which it is led and then carried around drive-wheel —5— to the bottom thereof, and then taken to the next adjacent drive-wheel —5— where this winding operation is 70 repeated. Each drive wheel —5— is in turn encircled in a similar manner by drive-wire —42— until the drive wire —42— is led back into the second slot —40— on the top of main drive wheel —17— and around said wheel, and through the hole in the slot —40— 75 into depression —37—, where it is fastened to one of the take-up screws —39—. This take-up screw —39— is then adjusted until the tension of the drive wire —42— is correct 80 throughout the circuit. When this result is achieved locking nut —39— and set screws —41— are tightened. Also drive wire —42— is secured to each drive wheel —5— by means of washers —51— and screws —52— disposed in cross slots —36—.

85 Drive cord 27 is then placed around the rim of main drive wheel 25 and drum 33 on knob 28. The tension on the drive wire 42 insures that the front ends of the rotor shafts 4 will always be held in the same position in relation to their bearings and to each other, and the spring wires —46— accomplish the same result for the rear ends of the rotor shafts —4—, which, taken together 90 with the extreme rigidity of the apparatus 95 due to the use of strip —2—, gives a rigid, permanent and efficient structure, not only mechanically but in the maintenance of a pre-determined electrical capacity of various 100 adjustments of the units of the apparatus, and altho we have shown and described a 105 specific structure as constituting an embodiment of the invention, we do not desire to restrict ourselves to the exact form or relation of the parts thereof, as various changes and 110 modifications may be made within the scope of the appended claims.

115 We claim:

1. A radio receiving apparatus comprising a plurality of condensers arranged in line, 110 and each condenser including a base, and arms extending therefrom, a sub-base, means for securing the condenser base to the sub-base, and a strip connected to the arms of the condensers to maintain them rigidly in 115 pre-determined relation.

2. A radio receiving apparatus comprising a plurality of condensers arranged in line, and each condenser including a base, arms extending therefrom, a sub-base, means for 120 securing the condenser base to the sub-base, and a strip connected to the arms of the condensers to maintain them rigidly in pre-determined relation, and having openings 125 through which the rotor shafts of the condensers extend.

3. A radio receiving apparatus comprising a plurality of condensers arranged in line, each condenser including a base, arms extending therefrom, a sub-base, means for se- 130

curing the condenser base to the sub-base, a strip connected to the arms of the condensers to maintain them rigidly in pre-determined relation, and means for actuating said condensers in unison.

- 5 4. A radio receiving apparatus comprising a plurality of condensers arranged in line, each condenser including a base, arms extending therefrom, a sub-base, means for securing the condenser base to the sub-base, a strip connected to the arms of the condensers to maintain them rigidly in pre-determined relation, and means for retaining each condenser rotor shaft in fixed relation to its bearing and to the other condenser rotor shafts.
- 10 15

- 20 25
5. A radio receiving apparatus comprising a plurality of condensers arranged in line, each condenser including a base, arms extending therefrom, a sub-base, means for securing the condenser base to the sub-base, a strip connected to the arms of the condensers to maintain them rigidly in pre-determined relation, spring means at one end thereof, and means for retaining each condenser rotor shaft in fixed relation to its bearing and to the other condenser rotor shafts.

In witness whereof we have hereunto set our hands this 30th day of June, 1927.

30 THEODORE J. SCOFIELD.
WILLIAM MINER.
